ROAD GUARD

William C. Martin and Donald Keith Macleod,
Wooster, Ohio, assignors to United Steel Fabricators, Inc., Wooster, Ohio, a corporation of Ohio

Application January 15, 1947, Serial No. 722,120

1 Claim. (Cl. 256—13.1)

1

This invention relates to guards for roads, highways and the like, and as one of its objects aims to provide an improved guard of this type which is of a very simple form of construction enabling the same to be economically manufactured and erected but which nevertheless is very rugged and durable.

Another object is to provide an improved road guard of this kind embodying supporting posts and a longitudinal rail and in which there are no sharp edges or abrupt projections located in exposed positions and on which personal injury would be sustained if a person were thrown thereagainst, and in meeting this condition the rail of the improved guard is so constructed that the top thereof forms a smooth continuous longitudinal safety edge.

A further object is to provide a road guard of this character in which the rail has longitudinal corrugations forming continuous longitudinal ribs on the traffic side of the guard and wherein the tops of such ribs and the top edge of the rail all have a smooth convex transverse curvature.

Still another object is to provide a road guard of the character mentioned in which the rail comprises a series of metal members which are tapered longitudinally and have their adjacent ends connected together by joints formed by having the small end of one member telescoped into the large end of the adjacent member.

As a further object this invention provides a road guard of this kind in which the large ends of the connected members point in the direction of traffic movement so that the "shingling" effect thus produced eliminates projecting shoulders on which personal injury could be sustained.

This invention also provides a road guard having a rail of increased "beam" strength through the use of oval-shouldered bolts for clamping together the telescoping portions of adjacent rail members.

Still another object is to provide an improved road guard in which the rail has a series of longitudinally spaced holes affording a selection or variation in the locations at which the supporting posts are to be set or driven.

Other objects and advantages of the invention will be apparent from the following description when taken in conjunction with the accompanying sheet of drawings in which

Fig. 1 is a perspective view of a road guard embodying the present invention;

Fig. 2 is a detached face view of one of the rail members as seen from the traffic side thereof;

Fig. 3 is a partial elevational view of the guard as seen from the traffic side thereof and showing

2

one of the supporting posts and a joint between two of the rail members;

Fig. 4 is a transverse sectional view, on a larger scale, taken through one of the rail joints as indicated by line 4—4 of Fig. 3;

Fig. 5 is a partial vertical sectional view taken through the rail and one of the supporting posts as indicated by line 5—5 of Fig. 3;

Fig. 6 is a sectional detail view taken transversely of one of the posts as indicated by line 6—6 of Fig. 5, and

Fig. 7 is another sectional detail view taken on line 7—7 of Fig. 5.

As one embodiment of the invention the accompanying drawing shows an improved road guard 10 comprising a series of spaced upright posts 11 and a continuous longitudinal rail 12 supported by such posts. As is usual in road guards of this character, the posts 11 are set or driven in the ground along the side of a road or highway and the rail 12 is attached to the posts on the traffic side thereof, that is to say, the side facing the road or highway.

The posts 11 can be of any suitable type or construction and, in this instance, are wood posts of a substantially square cross-sectional shape. Posts made of metal or other suitable material and posts of other suitable cross-sectional shapes could be used if desired. When wood posts are employed, the tops of the posts can easily be trimmed after they have been set or erected to a desired height so that the tops of the posts will bear a certain relation to the top edge of the rail, as is explained hereinafter.

The rail 12 is a continuous longitudinal metal rail formed by connected members or sections 14 which are of a suitable length enabling the same to be conveniently manufactured, transported and assembled. The members 14 are of a corrugated form and have an angular or re-entrant cross-sectional shape. As shown in the drawing the members 14 have two vertically spaced corrugations 15 and 16 therein which form continuous longitudinal ribs 15a and 16a on the traffic side of the rail. The corrugations 15 and 16 are connected by an intermediate web portion 17 which forms a continuous longitudinal flat face 17a on the rail.

It is an important characteristic of the improved road guard that the top of the rail 12 has a smooth continuous longitudinal safety top edge 18. The safety edge 18 is formed by an extension of the upper corrugation 16 and has a convex transverse curvature at the top or apex thereof which merges into the downwardly diverging flat longitudinal portions or legs forming, respectively, the upper web portion 16b of the corruga-

tion 16 and the rearwardly and downwardly extending flange 19. The transverse convex curvature and the smooth longitudinally continuous character of the top edge 18 contribute a safety feature or characteristic to the rail such that if a traffic accident should occur, as by an automobile striking the road guard and resulting in a person being thrown against the top edge of the rail, he will not be seriously cut as would be the case if the top of the rail were irregular or had an exposed sharp edge. The downwardly diverging relation of the flat longitudinal web and flange portions 16b and 19 provide the longitudinal safety edge 18 with increased width which renders it less harmful to persons thrown thereagainst. It is also important that the tops of the ribs 15a and 16a are longitudinally continuous and have a smooth transverse convex curvature and thus do not present sharp edges or projecting shoulders against which personal injury or vehicle damage would be likely to occur.

The longitudinally extending intermediate flat portion or strip 17 provides the rail with the flat face 17a which is adapted for flush or smooth engagement with the front faces 11a of the supporting posts 11. The cross-sectional shape of the members 14 is such that when the rail is secured against the posts by means of the connecting bolts 24, the top and bottom rear edges 22 and 23 will bear against the front faces 11a of the posts as shown in Fig. 5. Such engagement of these edges with the posts provides additional support for the rail which will enable the same to more strongly resist deflection or displacement due to impacts delivered thereagainst by vehicles.

Another novel feature of the rail members 14 is that the flat portions 17a thereof have holes 24 spaced therealong and certain of which are used for the bolts 21 by which the rail is mounted on the posts. By providing such a series of holes in the rail the positions at which the posts 11 are to be located can be shifted by small increments so as to avoid joints between the rail members 14 or to avoid stones or other obstructions which would interfere with a proper setting of the posts in the ground. The holes 24 are preferably in the form of oval slots as shown in Figs. 3 and 7 having their major axes extending longitudinally of the rail. The clamping bolts 21 have oval-shaped shoulders 21a thereon adapted to fit into the oval slots 24 for holding the bolts against rotation and thus facilitating the tightening of the nuts 21b thereon. These bolts also have smooth oval heads 21c thereon which present no abrupt projections adapted to cause vehicle damage or personal injury.

Another important feature of the improved road guard 10 is that the members 14 are tapered longitudinally for their full length and each member has a large end 14a and a small end 14b. When the members 14 are mounted on the posts 11 the small end 14b of one member is telescoped into the large end 14a of an adjacent member so as to form an overlapping joint 25 as shown in Fig. 3. The end portions 14a and 14b are provided with similarly located holes 26 which are brought into registration and through which the clamping bolts 27 extend. The holes 26 are similar to the above mentioned holes 24, that is to say, they are in the form of oval slots having their major axes extending longitudinally of the rail. The bolts 27 have smooth oval heads 27a and also have oval shoulders 27b thereon which fit into the holes 26 and have an axial length substantially

equal to the combined thickness of the telescoping portions.

By making the members 14 of a longitudinally tapered form so that the ends of adjacent members will have a telescoping engagement of an appropriate length with each other and by providing the oval holes 26 and the oval-shouldered clamping bolts 27, it will be seen that the "beam" strength of the rail 12 will have a maximum value because the joints 25 embodying these characteristics will be strong and rigid. The fact that the axes of the oval holes 26 extend longitudinally of the rail also minimizes the extent to which the rail is weakened by such holes. The oval shape for these holes holds the bolts against turning thus permitting a tight joint to be formed during erection of the guard. It will also be seen that by reason of the fact that the heads 27a of the bolts 27 are of a smooth oval shape they will not present abrupt shoulders or projections on the traffic side of the rail against which personal injury or vehicle damage might occur. When the above-described oval-shouldered bolts 27 are employed in the joint 25 only a small number of these bolts is required and hence the work involved in fabricating and assembling the sections 14 is lessened.

In accordance with another feature of the present invention the rail 12 is formed by assembling the members 14 so that the large ends 14a thereof "point" in the direction of travel of the traffic in the lane adjacent to the guard. When the members 14 are arranged in this manner the large ends 14a will provide a "shingling" effect for the joints 25 such that the overlap of the large ends will extend with the traffic and there will be no exposed shoulder or projection against which personal injury or vehicle damage could be sustained.

Reverting to the posts 11, it will be noted that the rail 12 is mounted on the posts so that the safety top edge 18 will extend above the tops of the posts as shown in Fig. 5. The tops of the posts are preferably cut or trimmed so as to provide a top surface 11b which slopes away from the rail. Since the tops of the posts lie below the safety edge 18 of the rail they will be shielded by the rail and will not present abrupt shoulders or projections against which a person would be likely to be injured.

From the foregoing description and the accompanying drawing it will now be readily understood that this invention provides an improved road guard which is of a very simple construction but which is nevertheless very rugged and durable. It will also be seen that the construction of the improved road guard embodies safety features and characteristics eliminating any exposed sharp edges or abrupt projections against which personal injury or vehicle damage would otherwise be likely to occur.

Although the improved road guard has been illustrated and described herein in some detail, it will be understood of course that this is not to be construed as a limitation and that the invention includes all changes and modifications coming within the scope of the appended claim.

Having thus described our invention, we claim:

A road guard comprising a series of spaced posts, and a metal rail attached to said posts and disposed on the road side thereof, said rail having a pair of vertically spaced longitudinally extending corrugations therein forming convex ribs on the road side of the rail and a longitudinally extending flat strip between the corruga-

tions and engaging the posts, the longitudinal lower edge of the lower corrugation being a continuous substantially flat longitudinal flange extending downwardly and rearwardly away from the road and engaging said posts and the longitudinal upper portion of the upper corrugation having an integral longitudinal extension thereon which is transversely curved away from the road and includes a substantially flat continuous longitudinal flange extending downwardly and rearwardly into engagement with said posts, said extension forming a continuous convex longitudinal top safety edge on the rail which projects above the highest point of the tops of said posts.
